UNITED STATES PATENT OFFICE.

RICHARD LABORDA, OF SAN FRANCISCO, CALIFORNIA.

FOOT-OPERATED ELEVATOR.

1,091,935.

Specification of Letters Patent. Patented Mar. 31, 1914.

Application filed June 14, 1913. Serial No. 774,472.

To all whom it may concern:

Be it known that I, RICHARD LABORDA, a subject of the King of Spain, and a resident of the city and county of San Francisco and 5 State of California, have invented a new and useful Improvement in Foot-Operated Elevators, of which the following is a specification.

My invention relates to improved foot 10 operated elevators wherein a car is provided with stirrups attached to cables that are wound on spring controlled drums, the tension of either spring being greater than the weight of the empty car and the stirrups 15 therein, and wherein the elevation of the said car is permitted by alternately transferring the weight of the operator from one stirrup to the other, and the objects of my invention are, first, to provide an improved 20 foot operated elevator that will present a series of alternately elevated supports for the feet of the operator, second, to provide means for elevating each support or stirrup separately and independently of the other 25 when the weight of the operator is removed therefrom, third, to provide means for controlling the descent of the operator, and fourth, to provide means for preventing the 30 elevation of the car and the stirrups there- in when the weight of the operator is removed from both stirrups at the same time, or when the car is not in use. I accomplish 35 these several features by means of the device illustrated in the drawings forming a part of the present specification wherein like numerals of reference designate similar parts throughout the said specification and drawing and wherein—

Figure 1 is a broken front elevation of the 40 foot operated elevator disclosing the manner in which the car is slidably mounted within the frame and the stirrups within the car, the spring controlled drums rotatably mounted on the top of the frame, one 45 portion of one of the drums being broken away disclosing the oppositely faced ratchets on the other drum, the centrifugal governor for controlling the descent of the car, and the latch for preventing the elevation of 50 the car by the spring controlled drums when the car is not in use. Fig. 2 is a broken sectional view taken on the line X—X of Fig. 1, looking in the direction indicated by the arrow. Fig. 3 is an enlarged side elevation 55 of one of the spring controlled drums disclosing the manner in which the weighted

levers engage the band brake members and the manner in which the said band brakes engage the brake drum. Also the springs which retain the weighted arms or levers 60 normally against fixed stops. Fig. 4 is a vertical sectional view taken through both spring controlled drums showing the manner in which the centrifugal governor is secured to the drums and the coiled springs 65 within the drums. Fig. 5 is a sectional view of one of the drums disclosing the manner in which the driving spring is connected to the shaft and to the drums.

This foot operated elevator is designed 70 for the purpose of reaching high shelves and other high places beyond the reach of a person standing on the floor, and may be also used in building construction, mine shafts and the like or any place where it is impracticable to build stairs or a power operated 75 elevator.

For convenience in drawing I have illustrated the device in a perpendicular position but in actual practice it is intended that 80 the elevator shall be leaned against the shelf or wall.

My invention consists chiefly in a suitable supporting frame 1 having a stationary shaft 2 secured to the upper portion thereof by means of the supports 2'. Rotatably mounted upon the stationary shaft 2 are the spring controlled drums 3 and 4 having ratchets 5 and 6, respectively, secured to the outer rims thereof. The ratchets on the 90 drum 3 are faced in a direction opposite to that in which the ratchets on the drum 4 are faced. Pawls 7 and 8 are secured to the counter-shafts 9 and 10 which are in turn provided with the depending levers 11 and 12 respectively, the said pawls 7 and 8 being adapted to engage the oppositely faced ratchets 5 and 6 of the drums 3 and 4 respectively, for the purpose of preventing the 95 said drums 3 and 4 from being rotated in a direction that will wind up the coiled springs 8 secured thereto and to the portion of the stationary shaft 2 within the said drums.

Cords 13 and 14 are secured to the lower 105 ends of the levers 11 and 12 respectively, and to a central cord 15, so that when the said cord 15 is pulled downward the said levers 11 and 12 will be moved toward each other and thereby disengage the pawls 7 and 8 from the ratchets 5 and 6 respectively.

Rigidly secured to the stationary shaft

and between the supports 2' thereof, are 5
brake drums 16, which are also adapted to
serve as bushings for the purpose of pre-
venting a lateral movement of the drums 3
and 4 upon the shaft 2. Rigidly secured to
the outer surfaces of the drums 3 and 4 are
pins 17 to which are pivotally connected the
band brakes 18 having hooked ends 20. The
band brakes 18 are adapted to engage the
10 surface of the brake drum 16 and check the
speed of the drums 3 and 4 to which they are
attached when the weight on the car during
its descent causes the said drums 3 and 4 to
rotate too rapidly, and are operated by
15 means of the weighted levers 22 which are
also pivotally mounted upon the pins 17,
and which are also provided with the hooked
ends 21, said hooked ends 21 being adapted
20 to engage the hooked ends 20 of the band
brakes 18 and press the said brakes against
the periphery of the brake drum 16 when the
centrifugal force due to the rapid rotation of
the drums 3 and 4 is greater than the tension
25 of the springs 23 which normally retain the
weighted levers 22 against the fixed stops 22'.

Slidably mounted within the supporting
frame 1 is a car 25 having stirrups 26 and
27 slidably mounted therein. A cable 28
30 has one end secured to the bottom of the
stirrup 26 and after passing under suitable
pulleys 29 and 30, secured to the bottom of
the car 25, is secured at the other end there-
of to the bottom of the stirrup 27.

A cable 31 has its upper end secured to
35 the drum 3 while its lower end is secured to
the top of the stirrup 27 within the car 25.
A similar cable 32 has the upper end thereof
secured to the drum 4 and the lower end thereof
to the stirrup 26. In this manner
40 the cable 31, stirrup 27, cable 28, stirrup 26
and the cable 32 form a continuous connec-
tion between the drums 3 and 4. The cable
28 which forms the lower portion of the said
continuous connection supports the car 25
45 as hereinbefore described.

The lower end of the supporting frame 1
is provided with suitable rollers 33 so that
the said frame may be transported easily.

A latch 35 is pivotally secured to the
50 upper end of the car 25 as at 36, the said
latch 35 being slightly longer than the dis-
tance between the pivot 36 and the vertical
member of the frame 1 so that any tendency
55 of the car 25 to move upward will cause
the said latch 35 to be jammed between the
said pivot 36 and the said member of the
frame 1. In this manner the car 25 is pre-
vented from rising when the car is not in
60 use and when the latch is in the position in-
dicated in Fig. 1 of the drawings.

The springs S, which are secured to the
drums 3 and 4 and to the stationary shaft 2
upon which the said drums are rotatably
mounted, are coiled about the said shaft 2
65 in opposite directions to each other. The

cables 31 and 32 are wound around the
drums 3 and 4, respectively, in opposite di-
rections to each other. Also each cable is
wound in a direction opposite to that in
which the spring secured to that drum is
70 coiled, so that when either cable is pulled
downward it will wind up the spring se-
cured to that particular drum to which that
particular cable is secured. Conversely,
when either cable is released the action of
75 the spring, secured to that drum, in unwind-
ing will rotate that drum and wind up the
cable thereon and thereby elevate the stir-
rup secured to that cable and the car 25,
providing the latch 35 has been released
80 from the vertical member of the frame 1.

The tension of either spring is sufficient
to rotate the drum to which it is secured
and to wind either cable thereon and ele-
vate the car 25 and the stirrups 26 and 27
85 therein, when the pawls 7 and 8 are released
from the ratchets 5 and 6, respectively, and
when there is no weight on the stirrups or
the car 25. When a weight greater than the
combined tensions of the springs S is placed
90 upon the stirrups 26 and 27, of the car 25,
the said car and stirrups are prevented from
moving downward and are supported by
means of the pawls 7 and 8 which engage
the ratchets 5 and 6 of the drums 3 and 4,
95 respectively, to which drums the said stir-
rups are secured. Should the pawls 7 and
8 be released, by means of the cord 15, from
the ratchets 5 and 6, respectively, the weight
of the operator standing on the stirrups 26
100 and 27 will pull the cables 32 and 31 down-
ward and cause the springs S to be wound
on the shaft 2.

The operation of the device is as follows:
Both feet of the operator are placed in the
105 stirrups 26 and 27 and the latch 35 is dis-
engaged from the vertical member of the
frame 1, the operator supporting the upper
portion of his person by taking hold of the
said vertical members. Inasmuch as the
110 ratchets 5 and 6 of the drums 3 and 4, re-
spectively, are engaged by the pawls 7 and
8 the weight of the operator on the stirrups
26 and 27, which are secured to the cables
32 and 31, respectively, will be supported
115 and the drums be prevented from unwind-
ing the cables thereon by means of the said
pawls 7 and 8. By raising the foot within
the stirrup 27 the tension of the spring S
will rotate the drum 3 and wind the cable
120 31, to which the stirrup 27 is secured, upon
the said drum. Simultaneously, the cable
28, one end of which is secured to the stir-
rup 27, will be raised and thereby elevate
the car 25 until the same comes into contact
125 with the bottom of the stirrup 26 to which
the other end of the said cable 28 is secured.
Also, while the stirrup 27 is being raised
by the drum 3, the pawl 8 engages the
ratchet 6 of the drum 4 thereby preventing
130

the said drum 4 from rotating in a direction that will lower the said stirrup 26 that is supporting the weight of the operator. By shifting the weight of the operator to the 5 stirrup 27 and raising the foot within the stirrup 26 the said weight will be supported by means of the pawl 7 which engages the ratchet 5 of the drum 3 so that the cable 31 thereon will not be unwound. Simultaneously, the weight having been removed from the stirrup 26, the spring S within the drum 4 will rotate the said drum and wind up the cable 32, thereby elevating the said stirrup 26 and the car 25. It is evident that by alternately raising the feet of the operator 10 the springs S will wind up the cable attached to the stirrups alternately and thereby raise the stirrups and the car until the desired elevation is attained. When the operator desires to be lowered the pawls 7 and 8 are released from the ratchets 5 and 6 of the drums 3 and 4, respectively, by means of the cord 15, which, when pulled downward, will draw the lower ends of the 15 levers 11 and 12 together and thereby withdraw or release the said pawls from the said ratchets. The weight of the operator being greater than the combined tensions of the springs S the said weight will lower the 20 car 25 and the stirrups 26 and 27 therein and rotate the drums 3 and 4 in a direction that will wind up the said springs ready for the next operation of elevating the car. The speed of the descent will be controlled by 25 means of the weighted levers 22 in the manner hereinbefore described. After the car has reached the bottom of the supporting frame 1 it is prevented from being elevated by the tension of the springs S by means of 30 the latch 35 which is placed in position before the operator removes his feet from the 35 stirrups.

It is obvious from the foregoing that I have provided improved means for elevating 40 an elevator car by alternately raising the feet of the operator and alternately shifting the weight of the said operator from one stirrup to the other. I have also provided means for controlling the descent of the operator and means for retaining the elevator 45 car at any point in the supporting frame.

The details of construction are so susceptible to variation that I do not wish to confine myself to the precise construction shown 50 and described herein but rather to avail myself of any modification that may fall properly within the scope of my invention.

Having thus described my invention what I claim as new and desire to secure by Letters Patent is—

1. A foot operated elevator comprising a suitable car; stirrups slidably mounted within the car; a suitable connection between the stirrups and adapted to engage the bottom of the car; a separate cable secured to

each separate stirrup; and spring controlled drums adapted to wind up the cables secured to the stirrups within the car and to elevate the said car when the stirrups therein are raised alternately.

70

2. A foot operated elevator comprising a suitable car; stirrups slidably mounted within the car; a suitable connection between the stirrups and adapted to engage the bottom of the car; a separate cable secured to each stirrup; spring controlled drums adapted to engage and wind up the cables secured to the stirrups within the car; and means for preventing the rotation of the drums in a direction that will unwind the cables.

80

3. A foot operated elevator comprising a suitable frame; a car slidably mounted within the frame; stirrups slidably mounted within the car; a suitable connection between the stirrups and adapted to engage the car; a separate cable secured to the top of each stirrup; and spring controlled drums rotatably mounted on the top of the frame and adapted to elevate the car by means of the cables secured to the stirrups within the 90 said car.

85

4. A foot operated elevator comprising a suitable frame; a car slidably mounted within the frame; stirrups slidably mounted within the car; a suitable connection between the stirrups and adapted to engage the bottom of the car; a separate cable secured to each stirrup; spring controlled drums rotatably mounted on the top of the frame and adapted to elevate the car within the frame 100 by means of the cables secured to each stirrup within the car; and means for preventing the car from being lowered.

95

5. A foot operated elevator comprising a suitable frame; a car slidably mounted within the frame; stirrups slidably mounted within the car; a suitable connection between the bottom of the stirrups and adapted to engage the bottom of the car; spring controlled drums rotatably mounted on the 110 top of the frame; a separate cable secured to the top of each stirrup and wound separately upon each drum; means adapted to prevent the cables from being unwound from the drums; and means for preventing 115 the car from being elevated when not in use.

105

6. A foot operated elevator comprising a suitable frame; a car slidably mounted within the frame; stirrups slidably mounted within the car; a suitable connection between the bottom of the stirrups and adapted to engage the bottom of the car; spring controlled drums having ratchets thereon and rotatably mounted on the top of the frame; a separate cable wound upon each 120 drum and secured to each stirrup; pawls pivotally secured to the frame and adapted to engage the ratchets on the drums for the purpose of preventing the drums from rotating in a direction that will unwind the 130

cables therefrom; means for releasing the pawls from the ratchets; and means adapted to prevent the elevation of the car when the same is not in use.

- 5 7. A foot operated elevator comprising a suitable frame; a car slidably mounted within the frame; stirrups slidably mounted within the car; a cable secured to the stirrups and adapted to support the car; a shaft 10 fixedly secured to the top of the frame; drums rotatably mounted upon the fixed shaft and having ratchets thereon; springs secured to the shaft and the drums thereon and adapted to rotate the said drums in opposite directions; a separate cable secured to each stirrup within the car and separately wound on separate drums; pawls pivotally secured to the frame and adapted to engage the ratchets on the drums for the 15 purpose of preventing the said drums from rotating in a direction that will unwind the cable thereon; a suitable cord adapted to release the pawls from the ratchets; and means for preventing the elevation of the 20 car when not in use.

8. In a foot operated elevator, the combination of a suitable frame; a car slidably mounted within the frame; stirrups slidably mounted within the car; a suitable cable secured to the bottom of each stirrup and adapted to support the car; a shaft fixedly secured to the top of the frame; drums rotatably mounted upon the said shaft and having ratchets thereon, the ratchets on one 30 drum being faced in a direction opposite to that in which the ratchets on the other drum are faced; springs coiled in opposite directions and secured to the fixed shaft and to the drums rotatably mounted thereon; a 35 separate cable secured to each stirrup within the car and separately wound on each separate drum and adapted to elevate the car within the frame when the drums are rotated by the springs secured thereto and 40 to the stationary shaft; pawls pivotally secured to the top of the frame and adapted to engage the ratchets on the drums for the purpose of preventing the rotation of the 45 said drums in a direction that will unwind 50 the cables thereon; a suitable cord adapted to release the pawls from the ratchets on the drums; a latch secured to the top of the car

and adapted to engage the elevator frame for the purpose of preventing the car within the frame from being elevated when the 55 said car is not in use; and means for controlling the speed of rotation of the drums when the pawls are disengaged from the ratchets thereon and the car and stirrups 60 therein are moving downward.

9. In a foot operated elevator, the combination of a suitable frame; a car slidably mounted within the frame; stirrups slidably mounted within the car; a suitable cable secured to the bottom of each stirrup 65 and adapted to support the car; a shaft fixedly secured to the top of the frame and having brake drums fixedly secured thereto; drums rotatably mounted upon the fixed 70 shaft and having ratchets on the outer rims thereof, the ratchets on one drum being faced in a direction opposite to that in which the ratchets on the other drum are faced; springs coiled in opposite directions 75 from each other and secured to the fixed shaft and the drums rotatably mounted thereon; a separate cable secured to each 80 separate stirrup within the car and separately wound upon each separate drum; pawls pivotally secured to the top of the frame and having depending levers secured thereto and adapted to engage the ratchets on the drums for the purpose of preventing the said drums from rotating in a direction 85 that will unwind the cables thereon and wind the springs secured thereto; a suitable cord secured to the lower ends of the depending levers secured to the pawls for the purpose of releasing the said pawls from the 90 said ratchets; a latch secured to the top of the car and adapted to engage the frame for the purpose of preventing the car from being elevated when not in use; and means arranged to engage the brake drums on the fixed shaft and to control the descent of the 95 car.

In witness whereof I hereunto set my signature in the presence of two subscribing witnesses.

RICHARD LABORDA.
